[57] CLAIM

The ornamental design for an emergency breathing gas container and control mechanism, as shown and described.

DESCRIPTION

FIG. 1 is a top rear perspective view of an emergency breathing gas container and control mechanism showing my new design;

FIG. 2 is a top plan view thereof;

FIG. 3 is a rear elevation view thereof;

FIG. 4 is a front elevation view thereof;

FIG. 5 is a side elevation view thereof;

FIG. 6 is an opposite side elevation view thereof;

FIG. 7 is a bottom plan view thereof;

FIG. 8 is a top rear perspective view of an emergency breathing gas container and control mechanism showing a second embodiment;

FIG. 9 is a top plan view of FIG. 8;

FIG. 10 is a rear elevational view of FIG. 8;

FIG. 11 is a front elevational view of FIG. 8;

FIG. 12 is a side elevational view of FIG. 8;

FIG. 13 is a opposite side elevational view of FIG. 12; and,

FIG. 14 is a bottom plan view of FIG. 8.
